UNITED STATES PATENT OFFICE.

JOHN D. LOOP, OF POMONA, CALIFORNIA.

CONTINUOUS INTERNAL-COMBUSTION GENERATOR.

992,891.

Specification of Letters Patent. Patented May 23, 1911.

Application filed March 9, 1909. Serial No. 482,412.

To all whom it may concern:

Be it known that I, JOHN D. LOOP, a citizen of the United States, residing at Pomona, in the county of Los Angeles and 5 State of California, have invented a new and useful Continuous Internal-Combustion Pressure-Generator, of which the following is a specification.

This invention relates to means for continuously generating or producing a condition of elastic fluid pressure by internal combustion, the main object of the invention being to provide for the production of elastic fluid pressure without the use of boilers 15 or other externally heated generators.

Other objects of the invention will appear hereinafter.

The accompanying drawing is a general elevation, somewhat diagrammatic, of a system of apparatus embodying the invention, the generator proper being shown in section.

The generator comprises a chamber 1 whose outer casing shell or wall is formed of steel or other material of sufficient 25 strength to stand the high pressure, and an inner chamber 2 whose shell or wall is formed of refractory material. The walls of the internal chamber are spaced from the outer wall at all sides and preferably at 30 top and bottom and the upper part or top of this combustion chamber communicates through perforations 3 with the outer chamber 1. A lateral extension 4 extends from the chamber 2 through the outer chamber 35 and through the outer casing, and a burner 5 is provided at the outer end of this extension, said burner being placed so as to direct its flame through the extension 4 into the combustion chamber 2. Said burner is provided with means for supplying oil and air thereto as hereinafter described. Extension 40 4 is also provided with a man-hole 6 for access thereto and with a spark plug 7 for ignition purposes.

45 At the upper part of chamber 1 above the chamber 2 is provided a deflector or spreader plate 8 and above said deflector is provided means, such as a spray pipe or tube 9, perforated to discharge water onto the top of 50 the said spreader plate and into the space between the said plate and the outer wall of chamber 1. Chamber 1 is further provided with a pressure gage 10 and a safety valve 11 at or near the top thereof and with a pet- 55 cock 12 at or near the bottom thereof.

The apparatus further comprises means

for supplying air, oil and water to the generator, said means comprising an air tank 13, oil tank 16 and water tank 17. Air tank 13 is connected to burner 5 by pipe 30 having 60 a valve 38 connected by a pipe 14 with a compressor 15. The said air tank is also connected to tanks 16 and 17 by a pressure equalizing pipe 18 provided with valves 19 and 20 whereby connection may be established or shut off from either or both the oil and water tanks. Said oil and water tanks are further provided with supply pipes 21 and 22 having valves 23 and 24, said pipes being connected respectively with any suitable sources of oil and water. Air tank 13 is also provided with a pressure gage 25 and safety valve 26. A pipe 27 leads from the lower part of the oil tank 16 through valves 28 and 29 to the oil burner 5, and a pipe 31 75 leads from the water tank 17 through a valve 32 to the water spray tube 9.

A supplementary gasoline tank 33 may be provided having a supply connection 34 provided with a valve 35 and an outlet connection or pipe 36 having a valve 37 and leading to the pipe 27 between the valves 28, 29 aforesaid.

Means are provided for storing and delivering the elastic fluid under pressure, produced by the above described apparatus, and for utilization of a part thereof in the compression of the air necessary to maintain the combustion, it being understood that this air must be compressed to a pressure at least 85 equal to that in the generating chamber. For this purpose the outer chamber 1 is connected by a pipe 40 with a storage tank or reservoir 41, having a delivery pipe 42 with a gate 43, said delivery pipe leading to any 90 suitable means for utilization of the elastic fluid pressure and said storage tank provided with a pipe connection 44 having a throttle 45, to the cylinder of an engine 47 mechanically connected to the compressor 100 15 to operate the same.

The operation is as follows: Ignition is first started by admitting gasoline at the burner and igniting the same by spark plug or otherwise. During this operation combustion may be supported by allowing air to pass in through the pipe 30 if any compressed air is available. Otherwise an outlet may be provided at the top of chamber 1, as by opening safety valve 11 so as to provide a natural draft. When the internal chamber has been well heated in this man-

ner the gasolene is turned off by valve 37 and the water supply is turned on by valve 32. The products of combustion leave the chamber 2 at a high temperature and entering chamber 1 they are mixed with the water issuing from the tube 9 in a divided condition and water is thereby converted into steam, the gases being at the same time lowered in temperature so that the outer wall of 10 the chamber 1 is not subjected to any temperature beyond that which is safe for an iron or steel shell to carry. The mixture of the products of combustion with the resultant steam passes from the generator, chamber 15 1 through the pipe 40 to the storage chamber 41 which is of sufficient strength to withstand the working pressure and is suitably insulated, as shown at 39, to retain the heat. A part of the elastic fluid thus stored 20 into the reservoir may be drawn off continually or from time to time, as required, through the delivery pipe 42 to any suitable consumption means, and another part is conducted through pipe 44 to the engine 47 to 25 drive the compressor 15 for supplying compressed air to tank 13 and to the burner 5. The connection 18 between the compressed air tank and the oil and water tanks serves to maintain the same pressure on all three 30 of these tanks so that the oil can be freely

injected into the combustion chamber and the water pass by gravity into the generator chamber, the pressure on the oil and water by reason of the aforesaid connection with the communicating tank serving to overcome 35 the pressure within the generator chamber.

What I claim is:

An internal combustion pressure generator comprising a casing forming an outer chamber, a shell of refractory material forming a combustion chamber within said outer chamber, said shell being spaced apart from the casing of the outer chamber and forming a space therebetween, a burner provided with means for injecting oil and supplying air 40 under pressure to the combustion chamber, a spreader plate above said combustion chamber extending beyond the shell thereof, means for supplying water to the outer chamber above the spreader plate, and means 45 for drawing off the resultant gases under pressure from the outer chamber.

In testimony whereof, I have hereunto set my hand at Los Angeles California, this 2nd day of March 1909.

JOHN D. LOOP.
